Inventor:
Eugene W. Vest.
By John C. Higgin
Atty.

UNITED STATES PATENT OFFICE.

EUGENE W. VEST, OF MULBERRY GROVE, ILLINOIS.

AIR VALVE FOR GAS BURNERS.

1,417,120.

Specification of Letters Patent. Patented May 23, 1922.

Original application filed December 13, 1919, Serial No. 344,566. Divided and this application filed July 30, 1920. Serial No. 400,148.

To all whom it may concern:

Be it known that I, EUGENE W. VEST, a citizen of the United States, residing at Mulberry Grove, Bond County, State of Illinois, have invented certain new and useful Improvements in Air Valves for Gas Burners, of which the following is a specification containing a full, clear, and exact description, reference being had to the accompanying drawings, forming a part thereof.

My invention consists in the novel disclosure hereinafter particularly described and distinctly claimed.

This application is a division of a prior application filed by me on December 13, 1919, Serial Number 344,566, for means for controlling the fuel and heat in ranges, stoves and furnaces.

The object of my present invention is to provide an improved air-valve for the gas-burners of ranges, stoves and furnaces, in which a gas-valve, a Bunsen burner, an air-throat for said burner, a slide-valve for controlling the entrance of air to said throat, an adjustable-plate on the said slide-valve, to vary the normal opening into said air-throat, a cam on the stem of said gas-valve; and a mechanical connection between said cam and said slide-valve, to cause the movements of said gas-valve stem and said slide-valve to be simultaneous, in regulating the supply of air and gas to the burner; and whereby the turning up or down of the gas by rotating said gas-valve stem will not close off the gas or air entirely.

A further object of my invention is to provide the discharge of the gas-valve with an improved detachable-tip, which is interchangeable with other like tips of different sizes; in combination with an improved gas-valve construction which shall be capable of being quickly disassembled and reassembled in changing the size of said detachable-tip, according to the service required.

A further object of my invention is to provide an improved means whereby the discharge-orifice of the discharge-tip of the gas-valve cannot be completely closed, and the gas cannot be completely turned off at the tip, and the burner will operate upon a very small quantity of gas, when turned down to the limit, without the trouble of relighting.

A further object is to provide the gas-valve stem with a detachable and interchangeable shut-off tip.

55

In the drawings,

Fig. 1 is a sectional side-elevation of my invention applied to a portion of a range or other gas-fired apparatus, and

Fig. 2 is a detail front-elevation of my 60 air-throat slide-valve and its operating cam.

The numeral 1 designates the wall of the range, stove, heater or furnace, to which the outer end of the usual mixing-pipe 2 of the burner is detachably connected.

65

A detachable gas-valve casting 3 is constructed with an air-throat 4, and is connected to said wall 1 by having its shank inserted through an opening in said wall and joined to the outer end of the said mixing-pipe 2 by means of a threaded coupling 5 into the threaded ends of which the adjacent ends of shank and said mixing-pipe are screwed, the said gas-valve casting being located, of course, upon the exterior of the gas-fired apparatus, for convenience during use.

70

An important feature of my gas-valve construction is the detachable (and therefore interchangeable) gas-discharge tip 6, which is removably secured by screw-threads 80 (or by any other common means) to the inner end of the horizontal gas-throat 7 of the said gas-valve casting 3, whereby the gas man or other attendant may quickly put on whatever size of tip he may think desirable 85 for the service required; and also important is the further feature of making the tip 8 of the gas-valve stem 9 detachable, that it may be replaced by a larger or smaller, or by a longer or shorter tip, as required by the 90 service.

85

A still further important construction is that the discharge-orifice of the said gas-throat tip 6 is so large that it cannot be completely closed by the said detachable stem-tip 8 which cooperates with it; whereby the gas-valve stem 9 can be turned to almost shut off the gas, but cannot completely turn off the gas at that point; thus enabling the burner to operate upon a very small quantity of gas when turned down to the limit, and avoiding the necessity of relighting the burner every time it has been turned down to its limit.

95

100

The numeral 10 designates the gas supply-pipe, to which the said gas-throat 7 of said gas-valve casting is detachably connected by means of a common union 11 and shut-off cock 12.

A very quick opening and closing of the said gas-valve stem 9 is obtained by the use of a coarse screw-thread thereon engaging corresponding threads upon the interior of 10 the stuffing-box member 14 of said gas-valve casting 3.

The customary stuffing-box gland 15 is threaded upon the outer threaded end of the said stuffing-box member 14.

15 Simultaneous regulation of the entrance of air to the air-throat 4, and of the gas supply to the said mixing-pipe 2, is secured by a vertical slide-valve 16, having in its lower portion an air opening 17 which registers 20 with said air-throat opening or entrance when said valve is moved to a position to uncover said entrance; the opposite edges of said valve being mounted to move in guides 18 located at the opposite sides of said air-throat; and a suitable mechanical connection between said valve and the said gas-valve stem 9, which will cause the latter and the valve to move in unison; whereby the turning up or down of the gas will also regulate 25 the air, and produce the Bunsen flame required for the most efficient and economical operation of the burner. See Fig. 2.

In the present illustration of this part of my invention, I have provided a cam 19, 35 which is fixed on the said gas-valve stem 9 at a point between said stuffing-box gland 15 and the stem handle 20; said cam being fastened on said stem by means of a common set-screw 21 in such a manner that the position of the cam may be changed when desired.

The said cam 19 is provided with an arcuate slot 22 whose walls are engaged by a projection 23 extending forwardly from the 45 lower end of the said slide-valve 16 into the said slot.

With such construction, when the said gas-valve stem 9 is rocked or rotated the said cam will cause a corresponding movement of the said slide-valve 16, and the air entrance of the said air-throat 4 will be more or less closed or opened.

The primary, or normal, relative positions of the said cam 19 and the said air-valve 16 55 are, preferably, those in which they are shown in Fig. 2, so that even when the gas-valve handle is in a "shut" position there will be sufficient gas entering the burner to prevent its extinguishment, and also there 60 should be a small opening (as shown) to the air-throat, to enable a small quantity of air to enter there, to maintain the minimum combustion of gas.

To facilitate the making of the proper adjustment between the said air-throat and

said slide-valve, I place upon the front face of the latter an adjustable plate 24 which is provided with a vertical slot 25 into which extends a guide-pin 26 fixed at its inner end in the said slide-valve 16 and engaging the 70 opposite walls of said slot, to retain said adjustable plate in a vertical position.

A common cap-screw 27 also engages the walls of said adjustable-plate slot 25, and is threaded into the said slide-valve 16 at a 75 point below said guide-pin 26, so that the head of said screw will clamp said adjustable-plate upon said valve at the desired adjustment to produce the small primary air-opening into said air-throat 4 by way of 80 the said opening 17 in said slide-valve.

By adjusting said plate 24 on said slide-valve in the manner just described, the small primary opening of the said air-throat 4 may be quickly made, to produce the most 85 economical operation of the burner, no matter what the pressure of the gas in the said gas supply-pipe 10 may be, and no matter what the vacuum of the chimney may be.

In other words, the said adjustable-plate 90 24 provides a quick and efficient means for varying the size of the normal or primary opening into the said air-throat 4 of the gas-valve, to correspond to the vacuum produced by the chimney, as well as to make 95 said opening smaller or larger, according to the pressure in the gas supply-pipe.

To further facilitate the making of the proper adjustments of the air-valve plate 24 and the cam 19, I provide the front face of 100 the said cam with a series of marks, or a scale, indicating the minimum, the maximum and the intermediate number of cubic feet of gas to be consumed per hour, and these consist in the present case of a series of numbers "10, 20, 30, 40, 50, 60, 70 and 80."

Adjustable stops, in the form of common split-pins 28, in the present instance, are mounted upon said cam 19, detachably in radial holes 29 bored in the edge of said cam, 110 so that said pins will extend across the said slot 22 of said cam at the desired points in the length of the latter, and limit the movement thereof from its minimum to its maximum setting-points.

The operation of my invention will be clear, without further description.

A common reticulated cone-shaped strainer 30, made of wire cloth or other suitable material, is fixed in the said air-throat 4 of 115 said gas-valve casting 3, to act as a strainer for the entering air, and to prevent back-firing.

I claim:—

An air and gas valve for the burners of 125 stoves, ranges and furnaces, comprising a Bunsen gas-burner casting, a gas-valve stem, an air-throat, an air-valve arranged to control the entrance of air to said air-throat, a cam on said gas-valve stem, a connecting- 130

means between said cam and said air-valve whereby both will move simultaneously when said stem is rocked or rotated, and an adjustable plate on said air-valve, for varying the size of the normal opening to said air-throat.

5 In testimony whereof, I have signed my

name to this specification in the presence of two witnesses.

EUGENE W. VEST.
